UNITED STATES PATENT OFFICE.

DENT PARRETT, OF CHICAGO, ILLINOIS, ASSIGNOR TO PARRETT TRACTOR COMPANY, A CORPORATION OF ILLINOIS.

DESIGN FOR A FRAME FOR TRACTORS.

51,424.

Specification for Design.

Patented Oct. 23, 1917.

Application filed June 25, 1915. Serial No. 36,392. Term of patent 14 years.

To all whom it may concern:

Be it known that I, DENT PARRETT, a citizen of the United States, residing at Chicago, in the county of Cook and State of Illinois, have invented a new, original, and ornamental Design for a Frame for Tractors, of which the following is a specification, reference being had to the accompanying drawing, forming part thereof.

Figure 1 is a view of the frame in perspective showing my new design.

Fig. 2 is a bottom plan view thereof.

Fig. 3 is a view of the same in rear elevation.

I claim:

The ornamental design for a frame for tractors as shown.

In witness whereof, I have hereunto subscribed my name this 18th day of June, 1915.

DENT PARRETT.
